DESIGN FOR AN IRON STAND

Philip P. Wriede, New York, and Herbert Pike,
Brooklyn, N. Y.

Application December 3, 1947, Serial No. 142,942

Term of patent 14 years

(Cl. D49—6)

To all whom it may concern:

Be it known that Philip P. Wriede and Herbert Pike, both citizens of the United States of America and residents of the city and State of New York, and Brooklyn, in the State of New York, respectively, have invented a new, original, and ornamental Design for Iron Stand, of which the following is a specification, reference being had to the accompanying drawing, forming part thereof, in which,

Fig. 1 is a top plan view of an iron stand, embodying our new design;

Fig. 2 is a front end view thereof;

Fig. 3 is a rear end view thereof; and

Fig. 4 is a side elevational view thereof.

We claim:

The ornamental design for an iron stand, substantially as shown.

PHILIP P. WRIEDE,
HERBERT PIKE.
